UNITED STATES PATENT OFFICE.

MISHAEL E. NORRIS AND JESSE L. NORRIS, OF TEMPLE, TEXAS.

COTTON-CLEANER AND GIN-FEEDER.

No. 846,421.

Specification of Letters Patent.

Patented March 5, 1907.

Application filed August 14, 1905. Serial No. 274,131.

To all whom it may concern:

Be it known that we, MISHAEL E. NORRIS and JESSE L. NORRIS, citizens of the United States, residing at Temple, in the county of Bell and State of Texas, have invented a new and useful Cotton-Cleaner and Gin-Feeder, of which the following is a specification.

This invention relates to gin-feeding devices of that class which include mechanism whereby the impurities, consisting of pebbles, twigs, bits of iron—such as nuts, bolts, nails, or the like—as well as dust and fine impure matter, is separated from the cotton before the latter is fed into the gin; and the objects of the invention are to simplify and improve the construction and operation of this class of devices.

With these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of the invention, it being, however, understood that no limitation is necessarily made to the precise structural details therein exhibited, but that changes, alterations, and modifications within the scope of the invention may be resorted to when desired.

In said drawings, Figure 1 is a vertical sectional view of a combined cleaner and feeder constructed in accordance with the principles of the invention. Fig. 2 is a side elevation of the same. Fig. 3 is a detail view of a portion of the adjustable toothed rock-shaft.

Corresponding parts in the several figures are indicated throughout by similar characters of reference.

The casing 1 of the improved cleaner and feeder is supported for operation upon a gin-stand of ordinary construction, the upper portion of which is shown at 2, said casing being of any desired width, usually of the same width as that of the gin-stand upon which it is placed for operation.

The casing is provided in its rear part with a flue 3, into which the cotton is fed. At the lower end of said flue is supported a roller 4, which is provided with longitudinal corrugations or indentations 5', into which heavy objectionable material—such as pebbles, bits of iron, twigs, and the like—may settle. The

rear wall of the flue 3, which forms a part of the casing, is bulged forwardly beneath the roller 4, concentrically with the latter, and is then extended downwardly, so as to form the back wall 4' of a chute 5, having an inclined front wall 6, which likewise constitutes a part of the casing. The casing further includes a front wall 7, which is bulged to form suitable compartments for a pair of rollers 8 and 9, the former of which is disposed above and in front of the corrugated roller 4 and the latter of which is disposed in front of and beneath the plane of the corrugated roller 4 and somewhat in advance of the roller 8. The front wall 7 terminates at its lower edge in a forwardly-inclined angular lip 10, overhanging an opening 11 at the upper edge of the front portion 6 of the casing, said upper edge being reinforced by a rib 12, with which an apron 13 is hingedly connected, said apron serving to guide the clean cotton into the gin.

Secured transversely in the casing between the rollers 4 and 9 and spaced from the back wall of the casing is a beam 14, at the upper edge of which is hingedly mounted a shield 15, said shield being connected with a shaft or rod 16, one end of which extends through the end of the casing and carries a lever-handle 16', adapted to engage a notched segment 17, whereby the shield 15 may be secured at various adjustments. At the lower front edge of the beam 14 is supported a rock-shaft 18, which likewise extends through the end of the casing and is provided with an adjusting-lever 19, engaging a notched segment 20, whereby it may be secured at various adjustments. The rock-shaft carries a plurality of teeth 21, constituting a comb, which, as will be seen, is adjustable with relation to the roller 9. A curved screen 22, concentric with the roller 9, extends between the beam 14 and the reinforcing-strip 12, with both of which the said screen is suitably connected.

Motion may be imparted to the shaft of the roller 8 by means of a belt 23 from the source of power. The shafts of the rollers 8 and 9 are connected by a twisted belt 24, whereby they are rotated in the direction indicated by the arrows in Fig. 1, and the shaft of the corrugated roller 4 has been shown as carrying a ratchet-wheel 25, operated by pawls 26 27, connected with a lever 28, which is connected by a pitman 29 with a wrist-pin 30 upon a disk 31, secured upon the shaft of

the roller 8. It is to be understood, however, that other suitable gearing may be employed for driving the several rollers.

In the bottom of the chute 5 is supported 5 a spiral conveyer 32, the shaft of which carries a band-wheel 33, connected by a belt 34 with a band-pulley 35 upon the shaft of the roller 9, whereby the spiral conveyer is driven at a speed which will be regulated by 10 the relative sizes of the pulleys 33 and 35.

In the operation of this device the seed-cotton is fed into the chute 3 and drops on top of the corrugated roller 4, the upper lead of which moves in a forward direction.

15 Heavy and objectionable material will settle in the corrugations or grooves of said roller and as the latter rotates will be discharged behind the shield 15 and be guided through the space or opening between the rear edge 20 of the beam 14 and the rear wall of the casing into the chute 5, where it is disposed of by the spiral conveyer 2. The roller 8, which is designated the "picker-roller," is provided with radially-extending teeth 36, which 25 carry the cotton in an upward and forward direction, delivering the same upon the roller 9, which is likewise provided with teeth 37. By the roller 9 the cotton is carried over the screen 22 to the outlet 11, 30 where it is intercepted by the lip 10 and delivered upon the hinged apron 14, whereby it is conveyed to the gin.

In its passage over the screen 22 the cotton is freed from dust and other fine impurities, which pass into the chute 5 and are disposed of by the conveyer 32. The hinged shield 15 serves a twofold purpose—in forming a guide over which the coarse impurities may slide downwardly in the direction of 35 the chute and also in serving to strip the cotton from the picker-roller in case it should exhibit a tendency to adhere to said roller and delivering it upon the cleaner-roller. The teeth of the latter in pulling the 40 fibers of the cotton between the teeth 21 serve to straighten the fibers and to loosen the adhering dust, which will thus more readily be separated through the screen 22.

This cleaning and feeding device is provided with an automatic feed cut-off attached to the breast of the gin-stand in such a manner that the feed is stopped by lifting the breast of the gin, throwing the ratchet out of gear. This device may be attached 45 to either friction or ratchet gearing.

Having thus described the invention, what is claimed is—

1. In a device of the class described, a feed-flue, a grooved separating-roller journaled near the bottom of said feed-flue and incased thereby, a shield supported hingedly

in front of said roller, a toothed picker-roller supported for rotation above and in advance of said corrugated roller and shield, and a cleaning-roller to which the cotton is delivered by the picker-roller.

2. In a device of the class described, a casing including a feed-flue, a corrugated separating-roller journaled near the bottom of said flue and incased thereby, a shield supported hingedly in front of said corrugated roller, a toothed picker-roller supported for rotation above and in advance of the shield and corrugated roller, and a toothed cleaning-roller supported for rotation below and in advance of the picker-roller to receive material discharged from the latter.

3. In a device of the class described, a casing including a feed-flue, a corrugated separating-roller journaled near the lower end of said flue and incased thereby, a picker-roller supported for rotation above and in advance of said corrugated roller, a cleaning-roller supported for rotation below and in advance of the picker-roller, a beam supported transversely in the casing, a shield connected hingedly with said beam between the corrugated roller and the cleaning-roller and extending in the direction of the picker-roller, a brace secured adjacent to a slot or outlet in the casing in front of the cleaner-roller, a screen connecting said brace with the transverse beam and extending beneath and concentric with the cleaner-roller, a chute beneath said screen, and a conveyer in said chute.

4. In a device of the class described, a casing including a feed-flue, a separating-roller journaled near the lower end of said flue, an angular lip overhanging a discharge-slot in the opposite side of said casing, a brace adjacent to the lower edge of said slot, a toothed cleaning-roller supported for rotation in advance of the separating-roller, a picker-roller serving to convey the cotton from the separating-roller to the feeding-roller, a beam supported transversely in the casing between the cleaning and separating rollers, a screen connected with said beam and with the brace and extending beneath the cleaning-roller, and a rock-shaft supported by the transverse beam and having teeth constituting a comb extending in the direction of the cleaning-roller.

In testimony that we claim the foregoing as our own we have hereto affixed our signatures in the presence of two witnesses.
